(57) **CLAIM**

The ornamental design for a device for displaying decorative items on a grave marker, as shown and described.

DESCRIPTION

FIG. 1 is an environmental view of a device for displaying decorative items on a grave marker showing my new design; FIG. 2 is a perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof. The broken lines in the figures depict environmental subject matter and form no part of the claimed design.
